DEVICE FOR USE WHEN DRAWING OFF
LIQUIDS FROM CONTAINERSFrederick John Trevallen Barnes, Brisbane,
Queensland, Australia

Application September 14, 1931, Serial No. 562,765

1 Claim. (Cl. 251—41)

The usual practice, when drawing petrol, benzine, water, or other liquids from drums and like containers, is to raise the container to the necessary height and fit a tap to the bung hole. Not only is it awkward in most cases to raise the container but the usual arrangement of tap is such that much time is lost in drawing off the liquid. The object of this invention is the provision of suitable means whereby the liquid may be withdrawn without raising the drum, without waste of liquid, without waste of time, and which permit of the tap being quickly opened and shut. Means are also provided which will ensure the delivery pipe attached thereto to be fully and quickly opened. By the use of my invention it is only necessary to remove one bung and the hole is then securely closed by my device and there is little fear of danger, which is always the case when, to hasten delivery, a second bung is removed.

In carrying the invention into effect an adapter is formed at its inlet so that it may be screwed into the bung hole. A pipe extends through this adapter from the bottom of the drum, the outlet being fitted with a tap which is formed so that it can be quickly opened and closed. A pin or other valve may be fitted to the outlet of the tap for use in cases where a hose is attached to the outlet of the tap. An air passage, fitted with a ball check or other suitable valve, leads through the adapter from atmosphere to or near the inlet thereof. The outlet end of the air passage is formed to receive a connection with an air pump. Modifications of the invention may be provided.

In order that the invention may be better understood it will now be more fully described with the aid of the accompanying drawing, in which

Fig. 1 is a side elevation;

Fig. 2 is a side elevation after certain parts have been moved;

Fig. 3 is a sectional elevation of a detail;

Fig. 4 is a top plan view of the arrangement shown in Fig. 2, and

Fig. 5 is a perspective detail of the adjustable head.

An adapter A is formed with a screw A¹ by which it may be screwed into the bung hole in the head (preferably) of the drum A², being secured by a lock nut A³ preferably provided with a washer A⁴ to permit of a tight joint being effected. A packing gland B is provided so that the pipe C may be secured in the adapter A against leakage. A filter C¹ is fitted in the coupling C² of the pipe C, the lower end C³ of the

latter being splayed. An annular air space (not shown) is provided in the adapter A around the pipe C. An air passage (not shown) leads from this space to atmosphere, a ball check or other valve (not shown) being provided in the passage. The outlet D³ of the passage, to which an air pump may be removably attached, is provided with a cap D⁴, which is in turn protected with a cover D⁵.

A valve E of ordinary formation may be fitted to the air inlet passage for reducing pressure when desired.

A bend F or coupling is screwed to the outer end of the pipe C and a tap G, as about to be described, is screwed thereto.

The tap body G is formed with an adapter G¹ by which it can be screwed into the bend F or a coupling on the pipe C, a lock nut G² with washer G³ being provided for making a tight joint. It is also formed with an outlet G⁴, to which a hose may be fitted if desired, in which case a valve G⁵ may be provided.

A valve seat H is provided in the tap body G. The outer end of the body A carries a valve stem H¹, a suitable packing gland H² being provided. A valve H³ is secured on the inner end of the valve stem H¹, and the outer end carries a head H⁴, preferably adjustable by means of the thread H⁵ on the stem H¹ and the lock nut H⁶ so that the pressure on the valve H³ may be adjusted as desired. The head H⁴ pivotally carries by trunnions H⁷ the L-shaped handle lever J, to which is pivoted at J⁵ the side bars J¹, which latter are also pivoted to the body G by trunnions J². The side bars J¹ are coupled by a bridge piece J³ to simplify construction and to add strength. The lever J may be secured, as by the padlock J⁴, against improper manipulation.

The device may be made of metals and materials best suited for their respective purposes, and the details of construction may be varied as desired so long as the essential features of the invention are retained.

The drum A² containing the petrol or other liquid is placed on end and the plug N¹ is unscrewed from the bung hole. The adapter A is then screwed in and the lock nut G² with washer G³ tightened until a tight joint is effected. The gland nut B, in the case of the arrangement shown in Figs. 1 and 2, is slackened so that the pipe C may be pushed down as far as desired or to the bottom of the drum A². The tap G is turned to the required direction and the

gland nut B tightened. The device is now ready for use.

The cover D⁵ and cap D⁴ are removed and a hand pump is connected to the valve D³ and air is pumped into the drum A², after which the pump is removed and the cap D⁴ and cover D⁵ replaced.

When it is desired to draw some liquid, the lever J is turned over, thus withdrawing the valve H³ from the seat H. The pressure of the valve H³ on the seat H may be adjusted by adjusting the position of the head H⁴ on the valve stem H¹ and locking in the altered position by the nut H⁶. This is done by engaging a suitable instrument such as a screw driver in the kerfed extension H⁸ on the outer end of the stem H¹.

When a hose or other pipe is attached to the outlet G⁴ the valve G⁵ may be manipulated to allow air to pass into the head of the hose or other pipe, which is then completely emptied.

Having now particularly described and ascertained the nature of my said invention and in what manner the same is to be performed, I declare that what I claim is:—

25 An improved device for use when drawing off liquids from containers, a tap body having an inlet end adapted to be connected to a container, an outlet leading from the body, a valve seat provided in the body between the inlet and the out-

let, a valve mounted in the body and including a valve head for cooperating with the valve seat, a stem projecting from the head and slidable through the end of the body opposite the inlet and having the outer projecting end threaded, a head adjustable on the threaded projecting part of the stem and provided with opposed trunnions, an L-shaped handle lever including a shank and spaced ears projecting at right angles from the shank and pivoted on the trunnions of the head 10 in such manner that when the valve head is in open position the ears of the handle lever are straddled about the outer end of the stem, a lock nut on the stem adjacent the head having trunnions, side bars arranged on opposite sides 15 of the body and having their ends pivoted to said body and to the ears of the lever, a bridge piece integrally connecting the side bars together and arranged on the side of the stem opposite the shank of the handle lever, an ap- 20 ertured lug on the tap body, the shank of the lever being provided with a slot in its outer portion and adapted to engage over the apertured lug, and means for releasably locking the lever so as to hold the valve head in closed position and 25 to also maintain the shank of the lever and the bars parallel to each other.

FREDERICK JOHN TREVALLON BARNES.
